FIG. 2.

FIG. 3.

FIG. 4.

INVENTOR:—
JOHN R. BERRY.
BY *Martin O. Smith*, ATTY.

UNITED STATES PATENT OFFICE

2,249,267

PERMANENT WAVE COMB AND SPREADER

John R. Berry, Los Angeles, Calif.

Application June 17, 1940, Serial No. 340,917

3 Claims. (Cl. 132—17)

My invention relates generally to combs and more particularly to a combination implement designed for the use of hairdressers in producing permanent waves and which implement includes a comb, a flexible rod-like member for spreading, stretching, and folding in the loose ends of the hair as the same is applied to the conventional rods used in permanent waving machines and to a key utilized for locking the rods after the hair has been properly curled thereon.

The principal object of my invention is, to provide a unitary structure wherein a comb and a plate that is designed to be gripped between the thumb and index finger of the operator's hand are formed from a single piece of material and mounted on a rod, preferably formed of resilient metal, so that the greater portion of said rod may be utilized in the spreading, flattening and stretching of the hair while the device is in use, and the opposite end of said rod being extended a short distance from the back of the comb to function as a key that may be conveniently employed in tightening and releasing the ratchet associated with the conventional curler rod.

A further object of my invention is, to provide a device of the character referred to wherein a tube, preferably of metal, is embedded in the back of the comb and the plate that is gripped between the thumb and finger, which tube provides a reinforcement for said comb and also provides a bearing for that portion of the rod that extends through the back of the comb and said plate.

A further object of my invention is, to provide a simple, practical and inexpensive combination tool that may be conveniently used by hairdressers engaged in preparing the hair that is to be permanently waved.

With the foregoing and other objects in view, my invention consists in certain novel features of construction and arrangement of parts that will be hereinafter more fully described and claimed and illustrated in the accompanying drawing in which:

Fig. 1 is a perspective view of a combination hairdressing implement constructed in accordance with my invention.

Fig. 2 is an enlarged longitudinal section taken on the line 2—2 of Fig. 1.

Fig. 3 is an enlarged cross section taken on the line 3—3 of Fig. 1.

Fig. 4 is an enlarged cross section taken on the line 4—4 of Fig. 1.

Referring by numerals to the accompanying drawing which illustrate a preferred embodiment

of my invention, 10 designates the back or body of a comb, the same having formed integral therewith a row of conventional comb teeth 11. The back or body 10 is formed with side faces 12 that are slightly concave and in order to increase the gripping effect of the thumb and fingers with the comb, the concave side faces 12 may be milled or provided with small corrugations.

Formed integral with one end of the body or back of the comb is a plate 13, the side faces 14 of which are concave longitudinally in order that said plate may be conveniently grasped between the thumb and index finger while the implement is being used as a hair spreader, and these concave side faces may be milled or provided with small corrugations.

Extending longitudinally through the back or body 10 and likewise through the center of the plate 13 is a tube 15, preferably of metal, the ends of which extend slightly beyond the outer end of the comb back 10 and the outer end of plate 13. The comb body, its teeth 11, and the plate 13 may be formed from any suitable material, for instance, light weight metal, or any of the plastics now on the market, and in order to firmly anchor the tube in the comb body and plate, said tube is positioned in the mold in which the comb and plate are cast.

Extending through tube 15 and suitably anchored therein is a rod 16 of resilient metal, for instance, stainless steel, and that portion 17 of the rod that projects beyond the plate 13 functions as a resilient finger for the spreading, flattening, and stretching the strand of hair as it is applied to the curler rod of the permanent wave machine and also for folding in the loose ends of the hair before the ratchet of the rod is manipulated to secure the hair thereon.

While the resilient finger 17 is being used for manipulating the hair, the comb forms a handle that is grasped in the hand of the user with the thumb and index finger engaging the concave side faces 14 of plate 13.

When the comb is used for combing out the strand of hair that is to be worked into a curl, the resilient finger 17 passes across the palm of the operator's hand and the plate 13 is gripped between the thumb and index finger.

Thus the implement can be very conveniently handled while being used as a comb or for spreading and stretching the hair while being applied to the curler rod. After the hair has been properly curled about the curler rod, the short end 18 of the rod that projects beyond the outer end of the comb handle 10 is utilized as a key for

tightening the ratchet of the curler rod to secure the curled hair thereon.

It will be noted that short portions of the tube 15 project beyond the ends of the back or body of the comb 10 and the plate or extension 13 thereof, such construction being provided in order to provide a firm support for the end portions of the members 10 and 13 which are generally formed of material such as hard rubber, Celluloid, plastics, or the like, and as a result of such support the tendency of the end portions of the parts 10 and 13 to break and chip away is minimized.

Thus it will be seen that I have provided a combination implement that may be conveniently employed by hairdressers while preparing hair that is to be permanently waved and which implement is simple in construction, inexpensive of manufacture and very effective in performing the functions for which it is intended.

It will be understood that minor changes in the size, form and construction of the various parts of my improved permanent wave comb and spreader, may be made and substituted for those herein shown and described, without departing from the spirit of my invention, the scope of which is set forth in the appended claims.

I claim as my invention:

5 1. A permanent wave comb and spreader comprising a comb including a back and comb teeth, a plate projecting from one end of the comb back, a rod of resilient material extending through the back of the comb and through said plate, a substantial portion of which rod projects from said plate and a short portion of said rod projecting from the end of the comb back and a reinforcing tube secured to said rod and extending through said comb back and said plate and the end portions of which tube extend short distances beyond the ends of said comb back and plate.

10 2. A permanent wave comb and spreader as set forth in claim 1 and the sides of said comb back and plate being provided with concave surfaces.

15 3. In a permanent wave comb and spreader, a comb comprising a back and teeth, a plate formed integral with one end of the comb back, 20 a separately formed tubular reinforcing member embedded in and extending lengthwise through said comb back and plate and a rod of resilient metal sealed in and extending through said reinforcing member, with a substantial portion of said rod projecting beyond the end of said plate and a short portion of said rod projecting from the end of the handle.

JOHN R. BERRY.
